UNITED STATES PATENT OFFICE.

MAX HERZBERG, OF NEW YORK, N. Y., ASSIGNOR TO EXCELLA CORPORATION, OF NEW YORK, N. Y., A CORPORATION OF NEW YORK.

PATTERN.

Application filed September 26, 1924. Serial No. 739,976.

To all whom it may concern:

Be it known that I, MAX HERZBERG, a citizen of the United States, residing at New York, in the county of New York and State of New York, have invented certain new and useful Improvements in Patterns, of which the following is a full, clear, and exact description, such as will enable others skilled in the art to which it appertains to make 10 and use the same.

This invention relates to an improvement in patterns and pattern sets, such as are utilized, for example in producing a garment.

It is an object of the invention to furnish an article of the nature stated, the proper employment of which will readily be apparent even to a person not versed in the use of articles of this type.

A further object of the invention is to be predicated to the provision of a pattern or pattern set which will be complete in itself in that by the practice of the present invention it becomes unnecessary to refer to instructions carried by a separate sheet or envelope.

Another object is that of providing a pattern unit or set adapted to be used in producing an article portion or portions corresponding to the pattern units, which article portions may be assembled in such a manner that a perfect article is readily producible by the layman.

Other objects of the invention will in part be obvious and will in part appear herein-after.

The invention accordingly comprises an article of manufacture possessing the features, properties, and the relation of elements which will be exemplified in the article hereinafter described and the scope of the application of which will be indicated in the claims.

For the fuller understanding of the nature and objects of the invention reference should be had to the following detailed description taken in connection with the accompanying drawings, in which:

Fig. 1 is a face view of one form of pattern unit produced within the terms of the present invention; and

Figs. 2 and 3 are similar, but fragmentary enlarged, views of different portions of this unit.

Referring primarily to the first figure, it

will be observed in the present embodiment 55 that the reference numeral 5 indicates one unit of a pattern set, this unit being preferably made of tissue paper, or other suitable material, and being conveniently of that type known as a cut pattern, in which the margins 60 of the pattern body correspond to the margins of the unit to be produced with the assistance thereof. Indicia may be incorporated in this unit, as for example the edges of the same may be notched as at 6, its body 65 being formed with perforations 7, and carrying a mark 8, which latter indicates the preferred disposition of the unit relative to the weave of the material which is to be cut with the assistance of the unit.

In addition to the foregoing indicia, it will be noted in the view referred to that the unit 5 may present upon its outer face, a duplicate in miniature of its body, as has been indicated at 9. This representation of the unit, 75 in addition to being of a similar outline, also preferably incorporates markings 10 and 11, indicating respectively the notches 6 and openings 7 of the pattern unit.

Now referring particularly to Fig. 2, in which the miniature representation has been illustrated in detail, it will be noted that the markings 10 and 11 are identified by suitable characters adjacent which, in the present instance, instruction phrases 12 are displayed. 85 By means of these characters and instruction phrases it will be obvious that no difficulty will be experienced in matching and otherwise properly correlating the various units and sections of the pattern itself. The 90 miniature representation 9 may present additional indicia, as for example the particular pattern section which it represents may be identified by a reference letter as at 14, which letter is carried within the body of the 95 miniature representation. Immediately adjacent this character the particular section may be identified by its proper name, as for example "Front right side of pattern", and the code number of the pattern may be given 100 so that no difficulty will be experienced in this collection.

Also in the present instance it will be noted that there is included within the miniature representation 9 a tabulation of 105 the number of pieces given, each being positively identified, and suitable instructions 15 may be provided at this point.

Finally referring to Fig. 3, in which according to the present embodiment the lowermost portion of the pattern body 5 has been illustrated, it will be noted that in the present instance the indicia on each pattern section of the set may include a representation in miniature of all the pattern sections, as at 16, 17, 18, 19, 20 (corresponding to 5), 21 and 22—all of these representations being identified so that the corresponding sections which they depict may readily be determined by an unskilled person, and further including the various salient features of markings, etc., etc. Also in this group of indicia and preferably immediately below the same, as has been indicated at 23, the method of laying out the various pattern sections to best advantage on the material to be cut has been shown, having in mind different widths and lengths of the material, it being furthermore noted that this group of indicia may embrace suitable clarifying instructions.

From the foregoing it will be appreciated that by means of the present invention a pattern unit or section is presented, which preferably forms one element of a complete pattern set, this section being of such a nature that all necessary instructions for the manipulation of the individual sections, the entire set or both, may be included within its area in such a manner that an unskilled person is capable of using the article or articles with facility. If desired, the body of the sections bearing this indicia may be printed or otherwise suitably treated in order that the miniature representation of the section may appear in sharp relief upon the face of the section, or if desired this miniature representation itself might be so tinted or printed as to achieve the effect desired.

Furthermore it will be noted, incident to the manner in which the indicia embracing the miniature representation is applied to the pattern body, that no confusion can arise in the mind of the operator employing the same. In other words, the margins of the body 5 are preferably free from all confusing indicia in that in the present instance the representation in miniature is located at a point relatively remote from these edges, and also due to the fact that the outline of this representation is preferably so disposed upon the body of the pattern unit that its various portions are substantially parallel to corresponding portions of the section edges of the body 5.

Thus it will be understood that all the objects of this invention are accomplished, and since certain changes may be made in the above article and different embodiments of the invention could be made without departing from the scope thereof, it is intended that all matter contained in the

above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A pattern section having instructive indicia thereon, including a representation in miniature of said section.

2. A pattern section, including a body presenting guide marks, indicia associated with said body and including a representation in miniature of said section together with instructions interpretative of the guide marks associated with the same.

3. A pattern section, including in combination, a body incorporating guide markings, said body also presenting indicia including a representation in miniature of said section and guide markings corresponding to the first named markings and associated with said miniature representation.

4. A pattern section, including in combination, a body incorporating guide markings, said body also presenting indicia including a representation in miniature of said section and guide markings corresponding to the first named markings and associated with said miniature representation, said indicia also embracing instructions interpretative of said last named markings.

5. A pattern section, including in combination, a pattern body and indicia associated with said body, said indicia including a representation in miniature of the pattern set of which said section forms a part.

6. A pattern section, including in combination, a pattern body and indicia associated with said body, said indicia including a representation in miniature of the pattern set of which said section forms a part, said indicia further including instructions for the use of said section.

7. A pattern section, including in combination, a pattern body and indicia associated with said body, said indicia including a representation in miniature of the pattern set of which said section forms a part, said indicia further including a representation in miniature of the particular section aforementioned and instructions associated with said last named representation.

8. A pattern section, including in combination a pattern body and indicia associated with said body, said indicia including a representation in miniature of the pattern set of which said sections forms a part, said section being formed with guide markings,

5 said indicia also including a representation in miniature of the pattern body with which it is associated together with guide markings corresponding to the markings aforementioned, and instructions interpretative of the use of such markings.

9. A pattern set, including a plurality of sections having cut edges to be followed in producing finished garment portions, one of 10 said sections including a body and an illustration upon the face of said body, said illustration including a miniature representation of the section upon which it appears and having indicia to be followed in manipulating and joining the various garment portions produced by the use of said pattern sections.

10. A pattern section having indicia thereon including a representation in miniature 20 of said section, said representation being

disposed upon said section at points relatively remote from the margins of the latter.

11. A pattern section having indicia thereon including a representation in miniature of said section, said miniature being disposed upon said section in such a manner that portions of its outline are arranged substantially parallel to corresponding portions of the section. 25

12. A pattern section including a body 30 having cut margins corresponding to the article to be formed with the assistance thereof, and indicia associated with said body and including a representation in miniature of said section, the outline of said representation having its portions disposed substantially parallel to the edges of said body. 35

In testimony whereof I affix my signature.

MAX HERZBERG.
